ELECTRONIC VACUUM TUBE

Adolph A. Thomas, New York, N. Y., assignor to
 Radio Corporation of America, New York, N. Y.,
 a corporation of Delaware

Application January 12, 1929, Serial No. 332,000
 Renewed June 24, 1935

7 Claims. (CL 250—27.5)

My invention relates to the art of electric vacuum tubes, usually called radio tubes, in which a controllable electron path allows the passage of current between the plate and filament electrodes. In prior tubes of this type, the only means employed to control the flow of electrons from filament to plate has been an interposed grid on which a variable potential is impressed. This grid is either in the form of a metallic mesh or a plate having slots through which the electrons must pass to reach the plate. The number of electrons that go to the plate depends not only on the potential of the grid, but on the size and arrangement of the holes in the grid. If an electron happens to pass far enough between the grid wires or the edges of a grid opening, it goes to the plate; if an electron is near enough to the metal of the grid, it either stays there or is repelled. The grid interferes physically with the flow of electrons to the plate, because it must be placed between plate and filament, and this necessarily lowers the efficiency of the tube. Furthermore, the arrangement of the grid causes the tube to have interelectrode capacity which causes trouble in radio receivers.

It is the object of the present invention to provide an electron tube free from a grid and its disadvantages. In my vacuum tube, the flow of electrons between filament and plate is controlled by a reflector electrode which throws the electrons against the plate. The number of electrons reaching the plate depends entirely on the potential charge of said electrode, whereby the electron control is rendered definite. There is no obstruction in the electron path, as in the old grid tubes, and substantially the full effect of the electronic output of the filament is utilized. Also, the inherent capacity in my tube is reduced to a negligible minimum.

The novel features and practical advantages of my invention will be understood from a description of the accompanying drawings, in which—

Fig. 1 illustrates a vacuum tube constructed in accordance with my invention;

Fig. 2 is a diagrammatic plan of the elements in the tube;

Fig. 3 shows a modified form embodying an additional reflector plate;

Fig. 4 is a diagrammatic plan indicating the electron path between the filament and plate electrodes of Fig. 3; and

Fig. 5 is a detached perspective of the parabolic reflector in Fig. 3.

Before beginning a description of the drawings, I wish to call attention to the fact that

the parts are shown for clearness in grossly exaggerated proportions. The tube as made for commercial use is intended to fit standard sockets and is of substantially the same size as the grid tubes heretofore used.

Referring to Figs. 1 and 2, the vacuum tube 10 is formed with the usual upstanding stem 12, which in this instance rigidly supports five metal rods numbered consecutively from 13 to 17. The rod 13 carries a lateral arm 18, preferably of 10 spring metal, to which the upper end of a filament or wire 19 is secured. The lower end of filament 19 is attached to rod 15. The arm 18 is so mounted that filament 19 is constantly held under tension. The arm 18 and filament 19 are 15 attached to their respective supports by means of welding or in any other practical way. The rod 15 is connected by a wire 20 to a contact pin 21, and a wire 22 connects rod 13 with a contact pin 23. These pins are mounted or embedded in 20 the insulating base 24 of the tube.

The rod 14 carries an electrode 25, which is a curved metal plate preferably (but not necessarily) in the form of a parabolic cylinder. The inner surface of this plate is smooth and polished. 25 Among metals suitable for this purpose I may mention tungsten, nickel, uranium and osmium. Platinum may also be used, but it is too expensive for commercial purposes. The member 25 need not be of the same metal throughout, 30 for its surface may be an electroplating on any suitable material. The upper end of rod 14 may be flattened to facilitate attaching the parabolic electrode 25, as by welding or otherwise. The arrangement of electrode 25 is such that the 35 electron-emitting filament 19 lies substantially in the focal axis thereof. The rod 16 carries a narrow metal strip 26 in the form of a cylindrical section. This curved strip, which may be of the same material as the electrode 25, is so arranged with respect to filament 19 as to prevent the escape of electrons without their being electrically reflected by the parabolic electrode 25. 40 In other words, electrons that pass directly from the filament 19 to the shield 26 are directed toward the parabolic electrode 25. The rods 14 and 16 are connected by conductors 27 and 28 to a contact pin 29 mounted in base 24. In this way, the electrodes 25 and 26 are always at the same potential. In some instances it may not 50 be necessary to connect the shield 26 to contact pin 29, but it may be left as an electrically inert member, since its function is to prevent electrons from travelling directly from filament 19 to the anode plate 38 arranged at the mouth of the 55

parabolic electrode 25. The anode 30, usually of nickel or nickel-plated metal, is mounted on rod 17 to which it may be attached by welding or otherwise. A wire 31 connects the rod 17 with the fourth contact pin 32.

The filament 19, which is a wire of tungsten or other electronic material, is connected in any suitable circuit for heating to the required temperature to cause the emission of a stream of electrons, as in the old type of vacuum tube. The parabolic reflector 25 is connected to one side of the input circuit and takes the place of the grid used in prior tubes. The anode plate 30 is connected to the positive side of the plate battery or other source of constant potential. These connections will be understood without the necessity of adding a circuit diagram. Assuming the tube to be inserted in a socket and properly connected in a radio circuit or other amplifying system, the operation taking place in the tube is something like this:

When the filament 19 is emitting electrons and there is no electric charge on the electrode 25, the latter simply acts as a reflector of electrons. That is to say, as the electrons approach the inner surface of member 25, they are reflected to the plate 30. In Fig. 2 the electron path from filament 19 to the parabolic cylinder 25 is diagrammatically indicated by radiating dotted lines 33, and the path of the electrons as they are reflected by member 25 to the plate 30 is conveniently indicated by parallel dotted lines 34. Since the filament 19 in the present arrangement constitutes the focal axis of the parabolic cylinder 25, the reflection of the electrons from the latter to plate 30 takes place to some extent in substantially parallel paths, in accordance with a well known law of the parabola. It is not necessary that the electrons shall be regularly reflected from the curved surface 25, because at any angle of reflection they will strike the anode plate 30. For example, the crossing line 35 may be the path of a reflected electron or stream of electrons after striking the surface 25 from filament 19. There are billions of electrons streaming from the filament at high velocity and their paths are too complicated to follow. Nor is it necessary to speculate upon the precise course that an electron will follow on reflection from the electrode 25, for all that matters is the fact that electrons reflected toward the positively charged anode plate 30 will reach that plate. A certain proportion of the electrons will doubtless be reflected regularly from surface 25, as that would be the shortest path to take, but this particular point is not important. It will therefore be understood that the dotted lines 33 and 34 in Fig. 2 are not intended to represent accurately the paths traversed by electrons, but are used as a simple convenient way to indicate the travel of reflected electrons from electrode 25 to anode 30. The cylindrical shield 26 is so arranged that no electrons can strike the plate 30 directly. Electrons that strike the cylindrical shield 26 are repelled toward parabolic cylinder 25, from where they are again reflected to plate 30. The path of such doubly reflected electrons is indicated by the dotted lines 35. It is clear, therefore, that the entire electron stream emitted by filament 19 is under the control of the parabolic electrode 25. As long as there is no electric charge on the parabolic electrode 25, there is a constant stream of electrons between the filament 19 and the anode plate 30, so that no current impulses are produced in the plate circuit.

Let us now suppose there is a positive charge on cylinder 25. The negative electron stream which is projected from the wire 19 against the cylindrical reflector 25 is held attracted to the surface of the reflector by this positive charge. If the cylindrical shield 26 is connected to the contact pin 29 and has the same electric charge as cylinder 25, the action referred to also applies to the shield. The number or percentage of electrons retained by the positively charged members 25 and 26 depends on the voltage of the charge and its strength in relation to the number of electrons emitted by the hot filament 19. The higher the positive charge on reflector 25, the greater will be the proportion of electrons that will stick to the surface of this electrode, so that a correspondingly smaller proportion of electrons travel to the anode plate 30. When the potential charge of cylinder 25 is negative, the electrons striking its surface will be instantly repelled and reflected against the plate 30, so that a correspondingly greater proportion of the electron charge reaches the anode plate. It will be seen from this that the intensity or density of the electronic stream between filament 19 and plate 30 depends upon, and is proportionate to, the character and intensity of the electric charge on the curved electrode 25. When this electrode has a maximum positive charge, the number of electrons reaching the anode 30 is a minimum and the plate current is correspondingly reduced. On the other hand, when the potential on electrode 25 is a maximum negative, the greatest number of electrons pass to the plate 30 and the plate current is correspondingly increased.

The important point to notice in the operation of my new gridless tube is that the entire electron charge emitted by the filament 19 is under the control of the electrode 25. In the old grid tubes, as explained in the first part of this specification, only those electrons that happen to pass through the grid openings far enough away from the metal of the grid will succeed in getting to the plate, irrespective of the potential charge on the grid. This operation is entirely eliminated in my new tube where the entire electron stream flows toward the charged reflector 25, which either reflects the electrons to plate 30 or retains them. In the old grid tubes, no plate current flows when the grid is highly negative. In the gridless tube above described, the plate current is a maximum when the reflector 25 carries a high negative charge, and this means that the reflector takes no current (or practically none) when the output of the tube is greatest.

Instead of using a straight filament 19 located in the focal axis of the parabolic cylinder 25, I may use a reflector in the form of a paraboloid in whose focus the electron-emitting cathode is mounted. The member 25 in Fig. 2 may be considered as a cross-section through a paraboloid in the focus 19 of which is an electrode in the form of a point or small button adapted to emit a stream of electrons. In a less efficient form of my invention, the shield 26 may be omitted, in which case a certain proportion of the electrons will reach the plate 30 directly without being reflected by the member 25. The precise dimensions and relative arrangement of the electrodes 19, 25 and 30 are a matter of experiment for each particular design of vacuum tube, depending largely upon the specific purpose for which the tube is intended.

In the modification of Figs. 3-5, the mounting and arrangement of the filament are the same

as in Fig. 1, and I have therefore used the same reference letters to indicate corresponding parts. In this case the filament 19 is mounted in the focal axis to a cylindrical reflector 25' mounted on a rod 14', which is not electrically connected to any one of the four contact pins at the bottom of the tube. The cylindrical reflector 25' is not intended to be connected in circuit, because its function is to reflect electrons and not to control them. The anode plate 30' of Figs. 3 and 4 is mounted on a rod 17', which (like the rod 17 of Fig. 1) is electrically connected to contact pin 32 through wire 31. The electron stream between the cathode 19 and anode plate 30' is controlled by a flat metal plate 36 rigidly mounted on one or two rods 37 and electrically connected to contact pin 29 by a wire 38. The plate 36 is arranged at such an angle to the parabolic reflector 25' and the anode plate 30' that the electrons approaching the surface of plate 36 are reflected to the control electrode 36, and from there they are reflected to the positively charged anode 30'. The reflector plate 36 is connected to one side of the input circuit, like the grid in the old type grid tubes. To prevent any electrons reaching the anode 30' without being under the control of the charged reflector plate 36, I interpose a shield 39 which may be a cylindrical strip formed integral with (or otherwise attached to) the parabolic reflector 25'. The shield 39 is so dimensioned and positioned that it covers the angle 40 in the diagram of Fig. 4 and therefore blocks the movement of electrons directly to the anode plate 30'. I do not say that the shield 39 is necessary in all cases, but I believe that it adds to the efficiency of the tube.

The operation of the tube in Figs. 3 and 4 is the same as that of the tube in Figs. 1 and 2, I need add but little to what has already been said. The only difference in the operation of the two tubes is that in Figs. 3 and 4 the electron stream reaches the charged plate 36 either directly from filament 19, as diagrammatically indicated by dotted line 41, or by reflection from member 25', as indicated by dotted lines 42. If the reflecting plate 36 has a positive charge, it will attract the electrons and hold them, or at least hold the greater proportion of them, depending on the value of the impressed voltage. When the charge on plate 36 is negative, the electrons are repelled and reflected to the plate 30'. In other words, the operation of plate 36 with respect to the anode 30' is the same as the operation of the reflector 25 in Fig. 1 with respect to anode 30. The number of electrons retained by the reflecting plate 36 depends on the character and intensity of the charge impressed on the plate. The reflectors 25' and 36 may be of the same material as the parabolic electrode 25 of Fig. 1. The parabolic reflector 25' is electrically inert and its function is to reflect electrons. The construction of Fig. 1 is preferable on account of its greater simplicity, because the member 25 combines the functions of the members 25' and 36 in Fig. 3. What has been said about the electron paths in connection with Fig. 2 applies also to Fig. 4.

Among the practical advantages of this new tube over the old-fashioned grid tube may be mentioned a greater amplification power, more positive control of the electron stream, and a minimum inherent capacity of the tube. In the old-fashioned grid tube, the control of the electrons depends upon the action of the interposed grid as a physical obstruction in the electron

path. That is to say—the control of the electrons depends entirely on how many succeed in passing through the openings or windows of the grid. In the present case, the charged electrode 25 (or 36) does not constitute a physical obstruction in the electronic path between the filament 19 and the anode 30 (or 30'), but it is a solid metal plate which attracts and holds a definite proportion of the electron emission in accordance with the potential charge existing on its surface. The electron control is therefore definite and positive. As for the inherent capacity of the tube, that is reduced to a minimum on account of the relative arrangement of the electrodes 25 and 30 (Fig. 1) or electrodes 36 and 30' (Fig. 3). In the old type grid tube, the inherent capacity is relatively large on account of the close parallel mounting of grid and plate. Also, it should be noticed that because of the inherently low capacity effect in my new tube, the tendency of self-oscillation is brought down to a minimum, and may indeed be wholly eliminated in a proper design of tube.

Although I have shown and described certain specific constructions, I want it understood that my invention is not limited to the details set forth. I have no doubt that changes and modifications are possible without departing from the scope of the invention as defined in the appended claims.

I claim as my invention:

1. A vacuum tube having an electrode substantially in the form of a parabolic cylinder for receiving and reflecting electrons, an electron-emitting filament located approximately in the focal axis of said parabolic cylinder, said filament being constructed to discharge electrons against said parabolic cylinder, whereby electrons striking said cylinder are reflected therefrom, said cylinder being adapted to receive variable electric charges for controlling the electrons that strike said cylinder, and a plate electrode mounted closely to said parabolic cylinder for receiving substantially the entire electron stream reflected from said cylinder.

2. A vacuum tube having an electrode in the form of a curved plate provided with a smooth solid inner surface capable of reflecting electrons, an anode in the form of a plate mounted with its ends closely adjacent the ends of said curved plate, whereby said plates form a practically enclosed space, and a cathode mounted in said space for emitting electrons to said curved plate which is mounted directly in the path of the electron discharge for reflecting the electrons to said anode in accordance with the potential impressed on said curved plate.

3. A vacuum tube having an electrode in the form of a curved plate provided with a smooth solid inner surface capable of reflecting electrons, an anode in the form of a plate mounted with its ends closely adjacent the ends of said curved plate, whereby said plates form a practically enclosed space, a cathode mounted in said space, and means in said space for preventing electrons reaching said anode without reflection by said curved plate.

4. A vacuum tube having a control electrode in the form of a substantially cylindrical solid plate adapted to be subjected to variable potential, an electron-emitting filament supported approximately in the axis of said cylindrical electrode which thereby is mounted directly in the path of electrons from said filament for reflecting electrons in accordance with the potential impressed on the control electrode, and an anode

- in the form of a flat plate mounted transversely of said cylindrical electrode and substantially closing the mouth thereof, whereby practically all electrons reflected by the cylindrical control electrode are received by the anode.
5. A vacuum tube having an electron-reflecting control electrode in the form of a substantially cylindrical solid plate, an electron-emitting filament supported approximately in the axis of 10 said cylindrical electrode, an anode plate mounted closely adjacent said cylindrical electrode for receiving substantially all electrons reflected by the cylindrical electrode, and means for preventing electrons reaching the anode without reflection by said control electrode.
15. 6. A vacuum tube having a first electrode for receiving and reflecting electrons, said electrode being adapted to receive variable electric charges, a second electrode mounted closely adjacent said 20 first electrode and adapted to operate as an anode, means between said electrodes for emitting electrons to strike the first electrode, and means positioning the first electrode to reflect electrons

to the second electrode in accordance with the electric charge on said first electrode, said anode being mounted to receive practically all electrons reflected by said first electrode.

7. A vacuum tube having a substantially parabolic electrode for receiving and reflecting electrons, an electron-emitting cathode located approximately in the focus of said parabolic electrode, said cathode being mounted to discharge electrons against said parabolic electrode, whereby electrons striking said parabolic electrode are reflected therefrom, said parabolic electrode being adapted to receive variable electric charges for controlling the electrons that strike said electrode, an anode mounted closely to said parabolic 15 electrode for receiving electrons by reflection from said parabolic electrode, and only four contacts projecting from said tube, one of said contacts being connected to said parabolic electrode, another contact being connected to said anode, 20 and the other two contacts being connected to the opposite terminals of said cathode.

ADOLPH A. THOMAS.
